CLAIM

The ornamental design for a cylindrical trigger dampening absorber, as shown and described.

DESCRIPTION

FIG. 1 is a perspective view of a cylindrical trigger dampening absorber showing our new design in an installation between the trigger mechanism and frame of a gun; FIG. 2 is another perspective view thereof;

FIG. 3 is a top view thereof;

FIG. 4 is a front view thereof;

FIG. 5 is a right side view thereof;

FIG. 6 is a back view thereof;

FIG. 7 is a bottom view thereof;

FIG. 8 is a cross sectional view taken along the line 8-8 identified in FIG. 5; and,

FIG. 9 is a cross sectional view taken along the line 9-9 identified in FIG. 5.

The evenly, broken lines showing the trigger mechanism and frame of a gun are for the purpose of illustrating environmental structure; the dash-dot broken line depicts unclaimed boundaries of the claimed design; the dash-dot-dot broken line in FIG. 5 depicts the cross-sectional planes; the broken lines form no part of the claimed design.

1 Claim, 3 Drawing Sheets
